F. L. SHIDLER

GOLF PRACTICE EQUIPMENT

Original Filed March 4, 1927

INVENTOR:
FRANK L. SHIDLER,
BY
Robert Burns
ATTORNEY.

UNITED STATES PATENT OFFICE.

FRANK L. SHIDLER, OF KANKAKEE, ILLINOIS.

GOLF PRACTICE EQUIPMENT.

Application filed March 4, 1927, Serial No. 172,726. Renewed November 10, 1927.

This invention relates to an equipment and practice means for use in learning and practicing what is known as "the follow or carry-through stroke" in the game of golf, and has for its object:—

To provide means comprising a ground target or mark convenient to the station of the player, a flight or guide strip or mark in aligned horizontal relation to said ground target, and a suspended destination target in vertical aligned relation with said ground target and with a remote portion of said flight strip, the designated elements or features being adapted to provide a guiding and a training means for a learner or a player in attaining a perfect carry-through stroke with the use of a practice club, preferably of a type capable of successive change in the weight of the club head from a primary excessive weight to a lighter final weight of the head. An example of such type of practice club heads forms the subject matter of a companion application for Letters Patent Serial No. 172,727, and all as 25 will hereinafter more fully appear.

In the accompanying drawing:—

Fig. 1, is a perspective view illustrating the preferred arrangement of parts in this invention.

Fig. 2, is a perspective view of the head portion of the preferred form of practice club.

In the usual instructions in the game of golf to the learner, are a number of standard lessons, such as proper stance of the feet, proper position or poise of the body, correct manner of gripping the club shaft, and other minor items, which are deemed of importance and necessary to be learned and effected before the student can expect to make a proper stroke in golf play.

An essential teaching following such preliminary training is the attainment of a perfect execution of what is known as the carry-through stroke, in which an absolute requirement is that from the instant the club head comes in contact with the ball, the club head must continue on to the completion of the stroke in the precise direction in which it is intended to drive the ball. Any variation from such requirement usually causes the ball to take flight in a corresponding direction, not desired by the player.

Experience has shown that it is very difficult to attain such carry-through stroke without the assistance of some equipment

and repeated instructions, and in many cases it may be found necessary to occasionally repeat the play, assisted by such equipment, in order that the muscles, body and other faculties be kept in proper condition to readily effect such carry-through stroke.

Among the reasons for failure to effectively attain and maintain such perfect carry-through stroke are the following:—

Daily vocations of the learner or the player do not bring into use all the muscles and faculties necessary in playing successfully, in that it cannot be expected that such muscles, etc. will respond properly, just when and how desired, when called upon to effect the golf stroke properly. In like manner, lack of opportunity to play regularly, or inability to engage in regular practice will tend to a like failure. And again, physical conditions, want of complete control of the eyes in executing the golf stroke and lack of coordination, in constructive practice, of the eyes, body and mind are largely responsible for poor results attained.

With a view to assist in overcoming the difficulties in learning above set forth, the present invention involves an equipment or apparatus as follows:—

Adjacent to the position of the player or learner, and upon the ground, floor or other horizontal surface employed, a ground target 1, usually a circular spot, is arranged or formed, and is intended to represent the tee or spot at which a golf ball rests in ordinary playing.

From the target or spot 1, a straight strip or mark 2 extends along the ground or other surface to constitute a guide or flight strip for the party practicing.

Above the flight strip 2 and in vertical alignment therewith, a destination target 3 is suspended by a flexible connection or cord 4, at a height above the flight strip and at a distance from the ground target 1, so that it will be in the path of the head 5 of a club stick 6 in the hands of the player, to be struck by such head when the player attains the perfect carry-through stroke and only then. With a view to the proper elevated position of the destination target 3, its flexible supporting connection 4 has an adjustable formation 4' of any usual and suitable construction, and while said flexible connection may depend from a convenient overhead ceiling, roof or the like, in the preferred construction shown in Fig. 1, the flexible supporting

connection 4, is attached at its upper end to one end of an arm or bar, 7, the other end of which arm is pivotally attached to the upper end of an upright stand or post 8, 5 having a base 9 adapted to rest upon the ground or floor and on a remote portion of the flight strip 2 as shown.

The destination target 3 will usually be of a spheroid shape, and preferably of a hollow sound emitting construction so that 10 when struck it will give an audible indication of the fact.

The practice club used will preferably be of the type described in detail in my aforesaid companion application for Letters Patent, Serial No. 172,727, in which the practice club head 5 is formed so as to receive a series of interchangeable excess weights 5' which are secured in a substantial manner to 20 the club head by suitable fastening means.

The present equipment and system of use is intended solely for practice and not for playing the game, and no ball is used in such practice, the omission being intentional, it 25 being very desirable that in order to attain perfect control of the eyes during practice, that the player should be clearly impressed with the fact that nothing takes flight during practice and that he is to direct his gaze 30 solely to the ground directly in front of himself during the entire time the stroke is being executed. In actual use the interchangeable series of excess weights 5' of the practice club are successively used, commencing 35 with the heaviest one and at the commencement of the practice exercise of the learner or player. The excessive weight of the club head thus provided enables the learner to accomplish the correct carry-through stroke with ease and a minimum effort on his part, 40 in that the compelling action of the excess weight, when once in motion, influences the learner's muscles, body, etc., to come into line and perform the exact functions and movements necessary to assist in making a 45 perfect stroke. As the practice lesson progresses, the learner automatically performs such movements and the same becomes easy and natural to perform without effort or 50 close attention to details. At this point in the progress of the learner, the lighter excess weights 5' are attached and used in sequence so that when the learner has worked down to the bare club head, with no excess 55 weight carried, it will be found that the control in making a carry-through stroke has passed from the club head to the learner's muscles, body, etc.

Having thus fully described my invention, 60 what I claim and desire to secure by Letters Patent, is:—

1. An equipment for golf and like practice and instruction comprising in combination, a ground target or mark, a flight strip or mark extending therefrom, a destination

target, and means for supporting the destination target in aligned relation above a part of the flight strip remote from the ground target.

2. An equipment for golf and like practice and instruction comprising in combination, a ground target or mark, a flight strip or mark extending therefrom, a destination target having a spheroid shape, and means for supporting the destination target in aligned relation above a part of the flight strip remote from the ground target.

3. An equipment for golf and like practice and instruction comprising in combination, a ground target or mark, a flight strip or mark extending therefrom, a destination target having a hollow sound producing spheroid shape, and means for supporting the destination target in aligned relation above a part of the flight strip remote from the ground target.

4. An equipment for golf and like practice and instruction comprising in combination, a ground target or mark, a flight strip or mark extending therefrom, a destination target, and means for supporting the destination target in aligned relation above a part of the flight strip remote from the ground target, the same comprising a portable stand, an adjustable arm at the upper end of said stand, and a flexible connection between an end of said arm and the destination target.

5. An equipment for golf and like practice and instruction comprising in combination, a ground target or mark, a flight strip or mark extending therefrom, a destination target having a spheroid shape, and means for supporting the destination target in aligned relation above a part of the flight strip remote from the ground target, the same comprising a portable stand, an adjustable arm at the upper end of said stand, and a flexible connection between end of said arm and the destination target.

6. An equipment for golf and like practice and instruction comprising in combination, a ground target or mark, a flight strip or mark extending therefrom, a destination target having a hollow sound producing spheroid shape, and means for supporting the destination target in aligned relation above a part of the flight strip remote from the ground target, the same comprising a portable stand, an adjustable arm at the upper end of said stand, and a flexible connection between an end of said arm and the destination target.

7. An equipment for golf and like practice and instruction comprising in combination, a ground target or mark, a flight strip or mark extending therefrom, a destination target, and means for supporting the destination target in aligned relation above a part of the flight strip remote from the

ground target, the same comprising a portable stand, an adjustable arm at the upper end of said stand, and a flexible and extensible connection between an end of said arm

5 and the destination target.

8. An equipment for golf and like practice and instruction comprising in combination, a ground target or mark, a flight strip or mark extending therefrom, a destination target

10 get having a spheroid shape and means for supporting the destination target in aligned relation above a part of the flight strip remote from the ground target, the same comprising a portable stand, an adjustable arm

15 at the upper end of said stand, and a flexible and extensible connection between an end of said arm and the destination target.

9. An equipment for golf and like practice and instruction comprising in combination, a ground target or mark, a flight strip or 20 mark extending therefrom, a destination target having a hollow sound producing spheroid shape, and means for supporting the destination target in aligned relation above a part of the flight strip remote from the 25 ground target, the same comprising a portable stand, an adjustable arm at the upper end of said stand, and a flexible and extensible connection between an end of said arm and the destination target.

30

Signed at Chicago, Illinois, this 26th day of February, 1927.

FRANK L. SHIDLER.
